UNITED STATES PATENT OFFICE.

FRANKLIN KING CHASE, OF TAUNTON, MASSACHUSETTS.

DESIGN FOR A STOVE-BACK.

SPECIFICATION forming part of Design No. 32,321, dated March 6, 1900.

Application filed December 18, 1899. Serial No. 740,831. Term of patent 31 years.

To all whom it may concern:

Be it known that I, FRANKLIN KING CHASE, a citizen of the United States of America, residing at Taunton, in the county of Bristol and State of Massachusetts, have invented a certain new and original Design for a Stove-Back, of which the following is a specification.

This invention is a design for a stove-back; and it consists in the peculiar arrangement 10 of parts, as will be described hereinafter and illustrated in the accompanying drawings, in which—

Figure 1 is a perspective view of a stove-back designed in accordance with my invention, and Fig. 2 is an end view of the same.

In carrying out my invention I provide a base-panel 1, swelled centrally and vertically, as at 2, the sides of said swelled portion gradually merging into the longitudinally-swelled 20 portions 3 and 4. This swelled portion is ornamented by a convex circular portion surrounded by a scroll, while the ends of the

panel 1 are also ornamented by a scroll to correspond thereto. Above the panel 1 is a second panel 5, slightly convex in cross-section and somewhat larger than the first-named panel, and at the juncture of these two panels is a projecting overhanging body 6, while at the top of the panel 5 a similar projecting overhanging body 7 is designed and connected 36 to 6 by the bracket-shaped members 8 and 9. Above the body 7 is arranged a vertical panel 10, ornamented by a fanciful design in harmony with the fanciful design on the panel 5.

I claim—

The design for a stove-back, substantially as shown and described.

In testimony whereof I affix my signature in presence of two witnesses.

FRANKLIN KING CHASE.
